STORAGE RACK FOR PAPERS

Vennice E. Mark, 1576 Fisk Road SE.,
Grand Rapids, Mich.

Filed May 25, 1960, Ser. No. 60,728

Term of patent 14 years

(Cl. D33—3)

FIG. 1

FIG. 2

FIG. 3

FIG. 4

Fig. 1 is a perspective view of a storage rack for papers embodying my design.

Fig. 2 is a side elevation of the storage rack for papers shown in Fig. 1.

Fig. 3 is an end elevation of the storage rack for papers of Fig. 1.

Fig. 4 is a plan view of the storage rack for papers shown in Fig. 1.

I claim:

The ornamental design for a storage rack for papers, substantially as shown.
